(57) **CLAIM**

The ornamental design for an exercise station, as shown and described.

DESCRIPTION

FIG. 1 is a front view of a first embodiment of an exercise station according to the present invention.

FIG. 2 is a perspective view showing the left side, front and roof of the exercise station shown in FIG. 1.

FIG. 3 is a right side view of the exercise station shown in FIG. 1, the left side being a mirror image.

FIG. 4 is a top plan view of the exercise station shown in FIG. 1.

FIG. 5 is a front view of a second embodiment of the exercise station of the present invention, the top view being the same as the view shown in FIG. 4.

FIG. 6 is a perspective view showing the left side, front and roof of the exercise station shown in FIG. 5.

FIG. 7 is a right side view of the exercise station shown in FIG. 5, the left side being a mirror image.

FIG. 8 is a bottom view of the exercise station shown in FIG. 1; and,

FIG. 9 is a bottom view of the exercise station shown in FIG. 5.
